United States Patent Office

Des. 226,638
Patented Apr. 3, 1973

226,638

POCKETBOOK

Henry C. White, 67 Green Hill Road,
Springfield, N.J. 07081

Filed Jan. 14, 1972, Ser. No. 218,050

Term of patent 14 years

Int. Cl. D3—02

U.S. Cl. D87—3 A

FIG. 1

FIG. 2

FIG. 5

FIG. 4

FIG. 1 is a front top perspective view of a pocketbook embodying my design, the pocketbook being in folded condition;

FIG. 2 is a bottom rear perspective view of the pocketbook shown in FIG. 1;

FIG. 3 is a top plan view of the pocketbook of FIG. 1 in open condition;

FIG. 4 is a front elevational view of the pocketbook in open condition;

FIG. 5 is a right end view thereof;

FIG. 6 is a bottom plan view;

FIG. 7 is a left end view; and

FIG. 8 is a rear elevational view.

I claim:

The ornamental design for a pocketbook, substantially as shown.
